UNITED STATES PATENT OFFICE

LUDWIG DENZER, OF HAMBURG, GERMANY

PAPER HOLDER FOR TYPEWRITERS

Application filed May 4, 1929, Serial No. 360,486, and in Germany March 28, 1929.

The object of the present invention is to produce a simple and efficient device for holding the paper on the platen of a typewriter so as to prevent it from bulging and creasing, 5 and the invention consists in the provision in the carriage frame of a pair of lever arms which are mounted by means of a sleeve on a rigidly-secured bar and fitted with spring catches which engage in notches in said bar so 10 as to maintain rollers, carried by the free ends of the arms, normally in contact with the platen, the notches being chamfered so as to cause the catches to be retracted when the arms are turned for separating the rollers 15 from the platen in order to admit the paper.

Fig. 1 of the accompanying drawings represents a front view of the device,

Fig. 2 is a top view of the same, and

Fig. 3 is a cross-section.

20 The platen *l* of the typewriter is mounted in the usual manner in the side plates *b* of a carriage frame. According to the invention a bar *a* is arranged parallel to the platen and secured rigidly to the plates *b*. On said bar a 25 sleeve *c*, which carries two lever arms *m*, is rotatably mounted. The free ends of the levers are connected by a rod *e* whereon rollers *f* are arranged so as to allow of being applied to the platen *l* for clamping the paper to the latter, the rollers being arranged to slide and rotate on the rod. Each arm *m* is fitted with a 30 spring catch *g* in the form of a bell-crank which is pivoted at *h* and which is controlled by a spring *k* situated in a slot in the arm. 35 The bell-crank has a nose piece *i* which works in a slot in the sleeve *c* and which bears under the influence of the spring against the bar *a*. The latter is formed with notches with which the nose pieces *i* normally engage so as to 40 maintain the rollers *f* in contact with the platen. The edges of the notches are chamfered so as to guide the catches into and out of engagement with the notches. The arms can therefore be deflectd, in opposition to the catches, for separating the rollers *f* from the platen in order to admit the paper. When the arms are returned, the catches snap into 45 re-engagement with the notches so as to press the rollers against the paper.

The arms are fitted with finger pieces *d* whereby they can easily be manipulated.

I claim:

1. In a typewriter, the combination with a carriage frame and with a platen in said frame, of a bar arranged parallel to the platen and secured to the frame, a sleeve arranged rotatably on said bar, a pair of lever arms secured to said sleeve, a rod connecting the free ends of the arms, rollers arranged rotatably and slidably on said rod and adapted to be applied by means of the latter to the platen, and spring catches pivoted to the arms and formed with nose pieces which engage through slots in the sleeve in notches in the bar so as to maintain the rollers normally in contact with the platen, the edges of the notches being chamfered so as to cause the catches to be retracted when the arms are deflected for separating the roller from the platen. 70

2. A structure as claimed in claim 1 wherein the arms are formed with finger pieces.

3. A structure as claimed in claim 1 wherein the spring catches have the form of bell cranks and wherein the springs of said catches 75 are accommodated in slots in the lever arms.

LUDWIG DENZER.
